WINDOW CONSTRUCTION HAVING RELEASEABLE SASH ENGAGING STRIP

Harold A. Etling, Marshallville, Ohio, assignor to
Weather-Seal Inc., Barberton, Ohio, a corpora-
tion of Ohio

Application August 16, 1950, Serial No. 179,804

8 Claims. (Cl. 20—49)

1

This invention relates to window casings and means for positioning windows in a window casing for conventional sliding movement in the casing and for convenient and ready removal from engagement with the casing for cleaning the window or other purposes.

Heretofore there have been various types of window constructions proposed by which a double hung window sash can be slid up and down, or back and forth in a casing for opening or closing the window, as desired. Other window constructions have been proposed utilizing some type of resiliently positioned strip or edge member which engages and positions at least one edge of a conventional double hung window sash for retaining same in engagement with a window casing for sliding movement therein. However, such resiliently positioned strip can be manually pressed outwardly laterally of a casing whereby such strip can be completely disengaged from the edge of the associated window or windows so that an edge of the window can be swung, or pivoted with relation to the depressed positioning strip to remove at least such edge portion of the window from engagement with the casing. Thus cleaning of the outer surface of such window or windows is facilitated as is the positioning, insertion or removal of storm windows, screens and the like, into and from engagement with the outer portion of the casing normally forming the outer portion of the house or other structure in which the window casing is positioned. However, all of such resiliently positioned edge strips and similar means known to me have been somewhat difficult to control in that it has been almost a two person operation to remove one of the windows from such a type of a window casing, and it has been particularly difficult for women to do by themselves since one had to depress the resilient edge positioning member or strip and at the same time support the window sash itself and swing the sash out of engagement with such resiliently positioned edge retaining strip or other similar member used. Likewise, in replacing the sash in a window casing, it has been somewhat difficult and cumbersome to reengage the sash with the window casing since by such action, the resilient edge engaging members in the casing must again be depressed or moved, while holding the sash, to permit reengagement of the sash with the window casing. Such action has been particularly difficult to perform since normally both sides of the window sash have had resilient edge engaging means provided therefor.

2

It is the general object of the present invention to avoid and overcome the foregoing and other difficulties with presently known types of constructions of the type indicated, and to provide a resiliently positioned edge strip for engaging and retaining a window sash in a window casing, which edge strip is characterized by its ability to be secured in an inoperative position in a casing.

10 Another object of the invention is to simplify the action of removing a sash from engagement with a window casing, and the reengagement thereof.

15 Another object of the invention is to separate the support of a sash from the action of releasing the window sash from a casing, in a window construction of the type indicated.

20 Another object of the invention is to provide a pivotal and sliding type of a window sash that can easily be constructed from a conventional double hung sliding window and a novel method of effecting such conversion.

25 Another object of the invention is to provide a lock device for retaining a retractable sash positioner strip in a window casing in an inoperative position and have a convenient release action provided for such lock.

30 Yet another object of the invention is to provide a releasable lock in a window sash edge engaging member wherein such lock will move by gravity automatically from its locked or operative position to the released position thereof.

35 Another object of the invention is to provide relatively inexpensive, but sturdy, neat appearing window sash engaging strips which are of substantially weather-tight construction.

The foregoing and other objects and advantages of the invention will be made more apparent as the specification proceeds.

40 For a better understanding of the present invention, reference should be had to the accompanying drawings which disclose one presently best known embodiment of the principles of the invention, and wherein:

45 Fig. 1 is a front elevation, partially broken away and shown in section, of a window construction embodying the principles of the invention;

50 Figs. 2 and 3 are enlarged horizontal cross sections, partially broken away, taken on lines 2—2 and 3—3 of Fig. 1;

Fig. 4 is a fragmentary vertical section taken on line 4—4 of Fig. 2 showing the edge engaging strip in its operative position; and

55 Fig. 5 is a section similar to Fig. 4 showing the

edge engaging strip in its retracted or inoperative position.

In referring to corresponding parts in the accompanying drawings and the following specification, corresponding reference numerals will be used to facilitate correlation between such parts.

Reference now should be had to the details of the structure shown in drawings and there is shown a casing which is indicated in general by the numeral 1. This window casing 1 is shown as positioning upper and lower sashes 2 and 3, respectively, as conventional double hung window sashes for sliding movement. The casing 1 is shown as including substantially conventionally positioned vertically extending frame members 4 and 5 on opposite sides of the casing 1, and the frame member 4 is shown as having guides or stops 6 and 7 positioned at opposite margins thereof on the inner and outer portions of the casing 1 with relation to the structure in which the casing is positioned. Likewise, similar guides or stops 8 or 9 are provided on the margins of the frame member 5 and these guides or stops aid in positioning the sashes 2 and 3 for sliding movement in the casing 1.

In order to position one edge of the sashes 2 and 3 in the casing 1, and to permit pivotal movement of the sashes as will hereinafter appear, the casing frame member 4 has secured thereto a pair of hinge and guide plates 10 and 11 that normally extend the height of the casing 1 and which are positioned in spaced but parallel relationship on the frame member 4. These hinge and guide plates 10 and 11 are adapted to receive and pivotally engage with hinge means 12 and 13 which are individually secured, respectively, to the upper and lower sashes 2 and 3, as by means of wood screws 14. Usually the hinge and guide plates 10 and 11 are secured to the frame member 4 by screws 15. Figs. 2 and 3 best show the construction previously referred to and it will be seen that the hinge and guide plate 10 has the lower sash 3 pressing against the front or inner surface whereby this plate 10 forms one positioning means for the lower sash 3. The remaining guide plate 11 forms the other member for defining more or less of a channel in which the edge of the lower sash 3 is received for sliding movement. The guide or stop 6 forms the other member for defining the position of the upper sash 2. Usually the hinge means or plates 12 and 13 provided are more or less roughly Z-shaped in section with one end portion of same being received within an edge recess 16 and 17 formed in the upper and lower sashes 2 and 3, respectively. These recesses 16 and 17 are adapted to receive therein a conventional spiral type sash balance 18 the lower end 19 of each which is engaged with the lower portion of the sashes 2 and 3. The hinge means used permit free sliding vertical movement of the upper and lower sashes in the hinge and guide plates 10 and 11 provided, whereas engagement between the hinge means used permits pivotal movement of the upper and lower sashes about the hinge and guide plates 10 and 11, as will hereinafter be described.

As an important feature of the invention, a pair of retractable edge strips are provided for being positioned in the planes defined by the window sashes 2 and 3 to temporarily or releasably engage the edge of same opposed to that secured to the hinge and guide plate means 10 and 11. A center guide or stop 20 is suitably secured to and extends from the vertically extending frame member 5. Elongate strips or rails 21 and 22 are snugly re-

ceived between the guides or stops 8 and 20, and 20 and 9 to form a substantially weather-tight connection therebetween, but still to permit relative movement between the strips 21 and 22 and their associated guide means. Figs. 2 and 3 of the drawings show that ribs 23 and 24 are formed on the strips 21 and 22 respectively, and are adapted to engage with edge grooves 25 and 26 formed in the upper and lower sashes 2 and 3, respectively. The strips 21 and 22 are forced laterally inwardly with relation to the casing 1 by conventional spring means, such as coil springs 27, that are compressed between the strips 21 and 22 and the associated casing frame member 5 whereby such strips or rails are forced or urged resiliently and continually inwardly of the casing for resilient engagement with the edge portions of the window sashes 2 and 3.

Fig. 3 of the drawings clearly shows that appreciable clearance is provided between the adjacent surfaces of the frame member 5 and the strips 21 and 22 when the springs 27 have urged such strips out to engagement with the sashes 2 and 3 whereby a force manually applied to the exposed surface of the strips 21 and 22 can move same towards the frame member 5 laterally outwardly with relation to the casing 1 against the force set up by the springs 27. Such outward movement of the strips 21 and 22 is of sufficient extent to disengage the ribs 23 and 24 from the grooves 25 and 26 in the window sashes to free such edges from the casing 1 and all means associated therewith. Accordingly, the sashes 2 and 3 then can be pivoted or swung inwardly of the casing about the hinges provided therefor. Usually the ends of the springs 27 engaged with the strips 21 and 22 are received in recesses 28a provided in such strips. Normally the strips 21 and 22 extend completely the vertical height of the casing 1 and are positioned thereby against any vertical movement.

An essential feature of the present invention is that the strips 21 are positioned by use of means which limit or curtail the extent of relative separating movement between the strips 21 and 22 and the frame member 5 with which they are associated. Accordingly, some means such as screws 28, which may have washers 29 associated with them, secure the strips 21 and 22 to the casing frame member 5 but permit the springs 27 to urge such strips into normally spaced relationship with such frame means.

Yet another important feature of the invention is that a rectangular lock plate 30 is engaged with each of the screws 28 and is adapted to aid in maintaining the strips 21 and 22 in their operative or inoperative position, dependent upon the specific positioning of such lock plate with relation to the screws at any given instance. These lock plates 30 are shown as being slotted at 31 with the slot extending substantially longitudinally thereof, and with a pair of upstanding side flanges 32 being provided in opposed relation on a pair of opposite sides of the lock plates 30. The flanges 32 engage with the washers 29 and such flanges are of proper depth or height that when the screws 28 are engaged with the flanged portion 32 of the lock plate 30, the strips 21 and 22 are moved to their positions adjacent the casing frame member 5, which is their inoperative position, and at which time the strips are not engaged with the sashes 2 or 3. Usually an end or stop flange 33 is formed on an end of the lock plate 30 and it protrudes farther from the plate than the flanges 32 to

form a convenient stop to limit relative movement between the lock plates and the screws 28 positioning same. Sliding movement of the lock plates from one position to another is facilitated by inclined end portions 32a on the flanges 32.

Fig. 5 shows that there is a little clearance between the strips 21 and 22 and the frame member 5 when the strips are inoperatively positioned. By this type of a construction, a person is able to depress the strips 21 and 22 further outwardly of the casing 1 when the strips are inoperatively positioned and it is desired to position same operatively. Such further movement of the strips 21 and 22 effects a release of the lock plates 30 and, since the end flanges 33 are normally at the lower ends of the lock plates 30 and the slots 31 are vertically positioned, will permit gravity to slide the lock plates from their positions forcing the strips 21 and 22 to their inoperative positions to released positions at which time the strips 21 and 22 will be automatically urged inwardly of the casing 1 for engagement with the grooves 25 and 26 provided in the sashes 2 and 3. Usually the lock plates 30 are received in recesses 34 that are formed in the exposed surfaces of the strips 21 and 22.

It will be appreciated that in some instances it may not be necessary to position the lock plates 30 in exactly the manner shown herein and such lock plates may have horizontal movement in some instances, or else the lock plates may have limited movement in a recess provided in the strips 21 and 22 and not have any slots formed in the lock plates and with the screw 28 or equivalent member merely engaging an edge portion of the lock plate which has limited movement in a positioning recess formed in the strips 21 and 22. Furthermore, in some instances it might be desired to invert the lock plates 30 and this would cause gravity to help draw the lock plates down into their positions locking the strips in inoperative positions. Rotary types of cammed or other lock means may also be used on the strips 21 and 22 to limit the positions of same. The strips 21 and 22 may even be positioned for longitudinal movement in some cases and have the lock and release means formed therein or secured thereto.

It should be observed that the construction of the invention can readily be made from a conventional double hung window casing by a relatively few simple operations. First of all, a guide stop would be removed from engagement with the vertically extending frame member 4 and a replacement or filler block 50 would normally be substituted therefor. Next the edges of the window sashes 2 and 3 adjacent this frame member 4 would be routed out or a groove would otherwise be formed therein for receiving the balances provided, if such edges had not previously been grooved. Then the hinge plate means 10 and 11 and the hinges 12 and 13 would be secured to the frame member 4 and the sashes 2 and 3, respectively and this portion of the construction would be complete. The conversion of the window sashes to a pivotal type of operation is completed by cutting off an edge portion of the sashes 2 and 3 so that such sashes extend in width across the casing 1 only to the innermost edge of the stop 20. Then the grooves 25 and 26 would be cut in the edges of the sashes 2 and 3 for receiving the retractable sash positioning strips 21 and 22 to be used in the casing 1. Such strips 21 and 22 would be suitably secured to the casing member 5 by the particular type of lock and securing means to be used in such a con-

struction, and the window casing would be effectively converted to a pivotal and sliding type of a double hung window.

In operation, it will be appreciated that the sashes 2 and 3 can be slid up and down in the casing 1 and the exposed portions of the strips 21 and 22 can be individually moved into an operative or inoperative position, as desired. The sashes 2 and 3 next would be shifted to their opposite positions, and the remaining lengths of the strips 21 and 22 would be exposed for varying the positioning thereof. Since the sashes 2 and 3 are completely supported on the hinge and side plates and hinge means shown in combination with the balances provided, the person releasing the sashes from the casing 1 need not support the sashes at such time, whereby engagement of the sashes with the casing, or release of same therefrom is greatly facilitated. Furthermore, the balances 18 may be so constructed that they will automatically swing a sash, when released from the casing 1, inwardly of the casing to secure an automatic releasing action of same from the casing.

From the foregoing, it is submitted that a relatively sturdy construction has been provided which permits a window sash to be readily engaged with the casing or be removed therefrom for pivotal and swinging movement with relation thereto whereby it is submitted that the objects of the invention are achieved.

While one complete embodiment of the invention has been disclosed herein, it will be appreciated that modification of this particular embodiment of the invention may be resorted to without departing from the scope of the invention as defined by the appended claims.

Having thus described my invention, what I claim is:

40. 1. Apparatus comprising a strip for engaging an edge of a window sash to aid in positioning same, spring means for engaging said strip to urge it towards a window sash engaging position, said strip being movable to a position out of engagement with a window sash by compression of said spring means, and releasable lock means for retaining said strip in its inoperative position, said lock means being permanently engaged with said strip and being changed from operative to non-operative position by relative longitudinal movement of said strip and lock means.
45. 2. Apparatus for securing a window in a window casing, which apparatus comprises a strip for engaging an edge of a window sash to aid in positioning same in a casing, spring means adapted to be compressed between a casing and said strip to urge it towards a window sash engaging position, said strip being movable to an inoperative position out of engagement with a window sash by compression of said spring means, and releasable lock means for retaining said strip in its inoperative position, said lock means having zones therein of different thickness.
50. 3. In apparatus as in claim 2, said lock means comprising screw means for securing said strip to a casing and permitting relative movement of said strip towards and from the casing, and a lock plate slidably engaged with said screw means on the face of said strip to be positioned remote from the casing, said lock plate having longitudinally spaced relatively thick and thin zones therein separately engageable with said screw means to control the positioning of said strip with relation to the casing.
55. 4. Apparatus as in claim 3, said lock plate being

movable from its position securing said strip in its inoperative position to its position releasing said strip by gravity when said spring means are further compressed by movement of said strip toward a casing when said strip is positioned in its inoperative position.

5. Apparatus comprising a strip for engaging an edge of a window sash in a plane defined by the sash to aid in positioning same, spring means engaging said strip to urge it towards a window sash engaging position, said strip being movable to a position in the plane of but out of engagement with a window sash by compression of said spring means, and releasable lock means for retaining said strip in its inoperative position, said lock means being permanently engaged with said strip on the surface thereof to be positioned adjacent the sash, said lock means being completely received in a recess provided in said strip.

6. In a latch, a lock strip having an elongate recess in one surface thereof, a lock plate slidably receivable in the recess in the lock strip, securing means having a head portion for engaging an outer portion of said lock plate for securing it in said recess in the lock strip and for engaging the lock strip to a support, and resilient means for urging said lock strip in a direction towards the head portion of said securing means, said lock plate being positioned by said lock strip in combination with the force exerted on said lock strip by said resilient means, said lock plate having a longitudinally directed slot extending therethrough, said securing means extending through said slot to permit movement of said lock plate with relation to said securing means and extending through said lock strip to position such strip,

said lock plate being of different effective thicknesses at different longitudinal portions of the slot therein to position said lock strip at different distances from a support with different longitudinal positions of said lock plate with relation to said recess.

10 7. In a latch as in claim 6, said lock strip being movable in the direction in which said recess extends thereto when said securing means engages the thickest portion of said lock plate to release said lock plate, said lock plate being movable longitudinally in said recess by gravity from a locked to an unlocked position.

15 8. In a latch as in claim 6, said securing means comprising a screw for extending through said lock strip to position it, and said lock plate having flanges for a portion of its length to form the thickest portion of such lock plate.

HAROLD A. ETLING.
